UNITED STATES PATENT OFFICE.

ALBERT L. COLE, OF AUBURNDALE, MASSACHUSETTS, ASSIGNOR TO UNITED COPPER FOUNDRY COMPANY, OF BOSTON, MASSACHUSETTS, A CORPORATION OF MASSACHUSETTS.

ELECTRIC CONTACT-SPRING FOR TROLLEY-HARPS.

No. 901,885.

Specification of Letters Patent.

Patented Oct. 20, 1908.

Application filed September 28, 1905. Serial No. 280,401.

To all whom it may concern:

Be it known that I, ALBERT L. COLE, a citizen of the United States, residing at Auburndale, in the county of Middlesex and 5 State of Massachusetts, have invented an Improvement in Electric Contact-Springs for Trolley-Harps, of which the following description, in connection with the accompanying drawings, is a specification, like 10 letters on the drawings representing like parts.

My invention relates particularly to overhead trolleys in which a trolley wheel is journaled in the arms of a harp at the free end of a trolley pole through which the 15 electric current is transmitted to the motor of the car, my invention residing in the provision of a contact spring for insuring constant electrical contact between the wheel and the harp.

20 I provide a co-axially-arranged spring which serves the double purpose of holding the wheel properly centrally supported and also of transmitting the electric current. In the preferred embodiment I provide a helical spring, washer-like in shape (and to 25 some extent in function), preferably provided with a central, cylindrical portion resting in a recess for positioning the spring and also serving to press the same constantly 30 forward against the ends of the hubs of the trolley wheel, said helical spring being removably held at one end in the adjacent arm, thereby coöoperating with the rotating wheel in giving more or less peripheral or 35 circumferential resistance to tilting or swaying motion of the wheel on its axle (which is quite liable to take place when the bearing has worn loose).

40 In the accompanying drawings in which I have illustrated a preferred embodiment of my invention, Figure 1 is a central vertical sectional view thereof in the direction of the axis of the trolley wheel; Fig. 2 is a fragmentary view thereof showing the main 45 features of my invention in side elevation; and Fig. 3 is a detail in side elevation of the contact spring.

Mounted between the forked upper ends 50 or arms 1, 2 of a harp 3 (which may be of any usual or preferred form) is a usual trolley wheel 4 mounted on an axle 5, these parts being shown in more or less conventional form and various constructional details thereof being omitted as not being es-

sential to a clear understanding of my invention. 55

Each arm of the harp is herein shown as provided with a recess 6, and in this recess is mounted the spiral end 7 of the contact spring 8 which constitutes the main feature 60 of my invention. This spring extends in a flat disk-like or spiral coil 9, preferably to a slightly greater diameter than that of the hub 10 of the trolley wheel, and its outer terminal 11 is made straight and bent slightly 65 laterally to enter a pocket 12 formed therefor in the arm of the harp head.

The spring 8 is normally compressed or held under tension, tending to expand, thereby holding all the parts snugly and yet 70 yieldingly.

It will thus be seen that I provide a spring which is at the same time a washer and a contact spring, serving both to transmit the current and to take all lateral thrusts of the 75 trolley wheel and maintain the latter in proper central position and vertical alignment. For instance, if the axial opening or bearing (a bushing usually being employed) becomes unduly worn so that the trolley 80 tends to wobble, it will be seen that the spring-washer at once counteracts this tendency by offering not merely a direct inward pressure in the direction of the axis, but also, because of the helical shape of the spring, offering a resistance in the plane of rotation 85 of the wheel. The contact spring, however, cannot become unwound or unduly strained because the outer end is held rigidly in the 90 pocket 12 and the inner end is held in the recess 6. This construction, moreover, is exceedingly simple and inexpensive to manufacture and at the same time offers a minimum 95 wearing surface with absolutely sure contact. The flexible washer effect and the capacity for yielding in all directions gives great endurance and wearing qualities. For these and other reasons I prefer, and herein claim, the combined washer and spring made out of wire wound as shown, but I do not restrict myself in all cases thereto, as my invention may be applied in sheet metal struck up to the required shape. 100

In practice, the opposite springs 8 are mounted in place with their ends 11 firmly 105 inserted in the pockets 12 and their spiral or tubular centers retained in the recesses 6. The trolley wheel 4 is then inserted between

them and the axle put in place and secured, the spiral centers of the washer-springs automatically centering the latter for receiving said axle. As the trolley rotates, it is tightly 5 pressed at the ends of its hub by the opposite washer-springs, the latter yielding both laterally and circumferentially to the varying movements of the wheel.

Besides the constructional features and advantages above pointed out, I wish to point out the additional distinguishing feature which resides in securing the washer portion of my device to the harp as distinguished from directly securing the contact-spring 15 portion. The helical part 7 is the portion of the device which maintains unremitting contact between the hub and the harp, and, therefore, constitutes the real contact spring, *i. e.*, the device which maintains perfect and 20 constant electrical circuit conditions, while the flat or spiral part 9 constitutes the washer-portion of the device and is the only portion of the device fastened to the harp. This is shown as inserted in a pocket, but it 25 will be understood that it may be secured in other ways.

Having described my invention, what I claim as new and desire to secure by Letters Patent, is:

30 1. A trolley harp, a trolley wheel journaled therein, and a combined washer and contact spring mounted between the hub of the wheel and the harp and comprising a normally compressed disk-like washer portion ex-

pansible both radially and transversely of 35 said wheel, extending co-axially of said hub.

2. A trolley harp, a trolley wheel journaled therein, and a combined washer and contact spring mounted co-axially between the harp and the hub of the wheel, said combined washer and spring consisting of a one-piece wire coiled into a radially extending flat washer portion provided with means for directly securing it to the harp. 40

3. A trolley harp, a trolley wheel journaled therein, and an electric contact in the form of a coiled spring mounted co-axially between the hub of the wheel and the harp, said spring having a flat or spiral portion acting as a washer and an adjacent helical portion. 45

4. A trolley harp, a trolley wheel journaled therein, and a coiled spring having a flat circumferential portion extending between the harp and wheel and a terminal portion removably mounted in the harp. 50

5. A trolley harp, a trolley wheel journaled therein, and a spring bent in a continuous coil having its opposite ends retained by said harp for holding the spring pressed against the hub of the wheel. 55

In testimony whereof, I have signed my name to this specification, in the presence of two subscribing witnesses.

ALBERT L. COLE.
